UNITED STATES PATENT OFFICE.

JACQUE C. MORRELL, OF CHICAGO, ILLINOIS, ASSIGNOR TO UNIVERSAL OIL PRODUCTS COMPANY, OF CHICAGO, ILLINOIS, A CORPORATION OF SOUTH DAKOTA.

PROCESS FOR REFINING OILS.

No Drawing.

Application filed August 28, 1922. Serial No. 584,870.

To all whom it may concern:

Be it known that I, JACQUE C. MORRELL, a citizen of the United States, residing at No. 208 South La Salle Street, in the city of Chicago, county of Cook, and State of Illinois, have invented certain new and useful Improvements in Processes for Refining Oils, of which the following is a specification.

19 This invention relates to improvements in the process of refining oils, and refers more particularly to the refining of cracked hydrocarbon oils with a high sulphur content produced from a raw oil stock having a high 15 sulphur content.

The practice of using a solution of litharge or lead monoxide in sodium hydroxide in conjunction with sulphur for the removal of sulphur compounds in oils is well known. 29 However, the mechanism of the reaction has remained obscure, and therefore, variations and improvements or departures from this method have been relatively few.

Heretofore, it has been the practice to agitate a solution of litharge in sodium hydroxide (sodium plumbite) with the oil to be treated, and after a period of time to add the flowers of sulphur. With the addition of the sulphur, a precipitate of lead sulphide is 20 formed.

There is however, a very objectionable feature under such a method of treatment. Although not generally known, sulphur is quite soluble in hydrocarbon oils, and no 35 amount of subsequent washing with water will remove this sulphur dissolved in the oil. Sulphur in solution in the oil is extremely objectionable, particularly when used as motor fuel, since it corrodes various metal 40 parts, especially brass and copper.

It is the purpose of this invention to eliminate this objectionable feature by the use of various compounds of sulphur, and in particular such substances as calcium, or magnesium sulphide or aluminum sulphide, which though substantially insoluble in water, hydrolyze when added to water forming precipitates of the corresponding hydroxides as well as hydrogen sulphide.

50 According to the present invention, the oil is first preferably treated with sulphuric acid in the proportion of say, 500 to 650 pounds of acid per 100 barrels of oil, sometimes preceded by a water wash. The oil may be 55 agitated in the presence of the acid for 15

to 20 minutes. This is followed by a water wash for 10 or 15 minutes and an alkali wash such as sodium hydroxide or like substances which are used as a base. 35-40 gallons of 6-12° B. caustic soda per 100 barrels of oil treated, I have found to be satisfactory. To the oil is then added sodium plumbite (litharge) dissolved in sodium hydroxide or potassium plumbite in the proportion of say, 5 barrels of 16-30° B. caustic 65 containing from 5-30 pounds of litharge for each 100 barrels of oil treated. After agitation with the plumbite solution, the latter is removed, and although not necessary, in addition it may be desirable to wash out 70 some of the remaining traces of the plumbite solution from the oil with water before subsequently adding the sulphide.

This removal of the plumbite solution prior to the adding of the sulphide is a wide 75 departure from the usual practice of adding the sulphur while agitating the oil with the plumbite solution. The reason for this is two-fold. First, the sulphide reacts with the plumbite solution causing unnecessary 80 waste. Second, it has been found in connection with the present invention that when a cracked hydrocarbon oil is treated with sodium plumbite solution, an organic compound of lead soluble in oil is formed. 85

Upon the addition of a small amount of sulphide of calcium magnesium or aluminum, or other metallic sulphide materials in the proportion of say, 4 to 20 pounds per 100 barrels of oil, which hydrolyze in water, 90 a precipitate of lead sulphide is immediately produced.

The lead sulphide is allowed to settle and may even be assisted by special treatment. The sulphide material is withdrawn from the 95 oil, and the oil is subsequently water washed to remove any traces of the remaining sulphide precipitate or sulphide solution. After this cleaning operation, the oil is distilled, preferably with the use of steam, producing 100 a clean, water white distillate having a sweet odor. The oil upon subsequent tests is absent from free sulphur, and the combined sulphur content is much lowered and changed in nature as subsequent specification and other tests show.

The principles involved in this invention, have been applied to cracked distillates from Mexican, California, Texas and other 110 high sulphur bearing oils with uniformly

good results in the production of water white products of sweet odor.

The method of procedure in the present invention may be varied somewhat in their sequence, and the ingredients altered without departing from the spirit of the invention.

The intermediate alkali wash succeeding the acid treatment may sometimes be dispensed with, or the plumbite may contain an alkali. It is understood that the proportions and concentration of treating agents may be varied within wide limits without departing from the scope of my invention.

I claim as my invention:

A step in a process for refining and purifying mineral oil, consisting in subjecting the oil to the action of alkali metal plumbite in water solution, in then removing substantially all the alkali metal plumbite solution from the oil, in then treating the freed oil with a metallic sulphide capable of hydrolyzing in water to complete the reaction of the plumbite solution, and in then removing the separated precipitate and sulphide compounds.

JACQUE C. MORRELL.
